UNITED STATES PATENT OFFICE.

WALTER JOHN FRYER, OF LONDON, ENGLAND.

AIR-TIGHT TIN AND CANISTER.

1,333,910.

Specification of Letters Patent. Patented Mar. 16, 1920.

Application filed April 24, 1919. Serial No. 292,247.

To all whom it may concern:

Be it known that I, WALTER JOHN FRYER, a subject of the King of Great Britain, residing at 157 Great Portland street, London, 5 W. 1, England, have invented new and useful Improvements in or Relating to Air-Tight Tins and Canisters, of which the following is a specification.

This invention relates to air-tight tins 10 and canisters of the kind sealed by a "tagger" top which is cut through by means of a cutter carried by the external lid of the tin when said cutter is moved from a normally inoperative to an operative position 15 and said external lid is rotated relatively to the tin. The present invention relates particularly to such air-tight tins in which the cutting is effected in the plane of rotation by a cutter which is automatically moved from its inoperative to its operative 20 position by the revolution of the external lid relatively to the tin. In such tins the "tagger" top is formed with a peripheral flange adapted to extend downwardly outside and be soldered to the peripheral wall of the tin, the overall diameter of the "tagger" top being greater than that of the tin by at least twice the thickness of said top, 25 while the depth of said flange is small compared with that of the corresponding flange of the external lid, so that a good joint is not made when the tin is subsequently used as a canister. The object of the present invention is to provide improvements in such 30 tins whereby they are rendered more suitable for use as canisters after the "tagger" top has been cut through and removed. A further object of the present invention is to 35 provide means for facilitating the cutting of the "tagger" top.

A tin or canister made in accordance with 40 this invention is formed with a portion of reduced diameter at its top of substantially 45 the same depth, in the direction of the axis of the tin, as the peripheral flange of the "tagger" top, the reduction in diameter being substantially equal to twice the thickness of the "tagger" top, so that when the 50 "tagger" top is soldered in position a substantially flush surface is presented.

When the tin is used as a canister after 55 the "tagger" top has been cut through and removed the external lid fits closely around the flush surface throughout the depth of its 60 peripheral flange thus making a substantially air-tight joint.

As above set forth the cutter is adapted to be moved from an inoperative to an operative position by rotation of the external lid 60 of the tin and continued rotation results in the "tagger" top being cut through. The portion of the "tagger" top presented to the cutter (hereinafter referred to as the "tagger" portion) lies flat against or parallel 65 with the inner periphery of the tin, and after the cutting has been performed a short depth of the "tagger" top remains, the point of the cutter projecting under its lower edge. When the external lid is removed 70 the projecting cutter is apt to catch under the "tagger" portion and pull it upward and inward thus leaving a sharp protuberance which is liable to cause injury to the hand when inserted into the canister. A 75 further feature of this invention is the provision of means to overcome this disadvantage, said means consisting of a cutter whereof the point is sufficiently hard to 80 penetrate and cut the "tagger" portion, and whereof a portion remote from said point is softer so that said cutter is capable of being bent along a line substantially tangential to a circle of slightly smaller 85 radius than, and concentric with, the inner circumference of the "tagger" portion whereby, when the external lid of the tin is removed after the "tagger" top has been 90 cut through, the projecting point of the cutter will be bent downward as a result of its engagement with the lower edge of the "tagger" portion during the upward movement of the lid. This downwardly bent point of the cutter will also serve, during 95 any subsequent rotation of the lid relatively to the tin, to burnish the "tagger" portion, and remove any slight protuberances or roughnesses which may have resulted from the cutting of the "tagger" top.

In order to assist in the relative rotation of the external lid and the tin, the peripheral flange of the former is preferably provided externally with a series of protuberances to facilitate a grip being obtained 100 thereon. These protuberances may be pressed out from the metal itself, and extend over part only of the depth of said flange or soldered thereto, or a knurled band may be secured to the peripheral flange.

Referring to the accompanying drawings which illustrate one form of air-tight tin made in accordance with this invention, and in which the thickness of the parts and their

closeness to one another are exaggerated for the sake of clearness, Figure 1 is a sectional elevation, on the line 1—1, Fig. 2, Fig. 2 is a plan thereof, the cutter being shown in 5 dotted lines, in its inoperative position. Fig. 3 is an inverted plan of a portion of the lid, showing the cutter in its inoperative position. Fig. 4 is a fragmentary plan, parts being broken away and sectioned, showing 10 the cutter in its operative position. Fig. 5 is a similar view to Fig. 4, but showing the point of the cutter bent down alongside the "tagger" portion, and Fig. 6 is a section on the line 6—6, Fig. 5.

15 As shown in Fig. 1, the tin or canister *a* is provided with a neck *b* of less diameter than the main peripheral wall, secured to the upper edge thereof by a beading *c* and formed with a portion *d* of reduced diameter at its top, of substantially the same depth, 20 in the direction of the axis of the tin, as the peripheral flange *e* of the "tagger" top *f*, the reduction in diameter being substantially equal to twice the thickness of the "tagger" 25 top *f*, so that when said "tagger" top is soldered in position around the portion *d* a substantially flush surface is presented as shown in Figs. 1 and 6. This flush surface enables the peripheral flange *g* of the external lid *h* to fit closely therearound 30 throughout its depth, and make a substantially air-tight joint after the "tagger" top has been cut through and removed.

The external lid *h* is provided with a cutter *j* of stamped steel partially revoluble in 35 a bearing in said lid, and formed with a cutting point *k*, and with a downturned lug *m*. The lug *m* is adapted to coact, when the lid *h* is revolved relatively to the tin *a* in the 40 appropriate direction, with any one of a series of upwardly and inwardly indirected cams *n* . . . formed on the "tagger" top *f* and lying in the path of said lug, and in riding up the face of such cam to partially 45 revolve the cutter *j* from the inoperative position shown in Fig. 2 to the operative position shown in Fig. 4, and to force its point *k* into the "tagger" portion *o*. Continued rotation of the lid *h* causes the point *k* to 50 be carried around and to cut through the "tagger" portion *o* the lug *m* taking an abutment against the wall *p* of a recess *q* stamped up in the lid *h* and in which the lower portion of the cutter *j* lies. The point 55 *k* is sufficiently hard to penetrate and cut the "tagger" portion *o*, but remote from said point the cutter *j* is softer so that when the lid *h* is removed from the tin *a*, after the "tagger" portion has been cut through, the 60 point *k* engages the lower edge of the remainder of the "tagger" portion and is bent downwardly as shown in Figs. 5 and 6 along a line substantially tangential to a circle of slightly smaller radius than, and concentric 65 with, the inner circumference of the "tag-

ger" portion *o*. As shown in Fig. 6 this downwardly bent point *k* lies close to the lower edge of the remainder of the "tagger" portion *o*, so that during any subsequent rotation of the lid *h* it serves to burnish said 70 lower edge and remove any slight protuberances or roughnesses which may have resulted from the cutting of the "tagger" top.

In order to facilitate a grip on the lid *h* during rotation hereof its flange *g* is stamped 75 with a series of protuberances *r*, which extend over part of the depth of said flange.

I claim:

1. An air-tight canister comprising a body, a thin metal top whereby said body is sealed, an annulus constituting part of said top and engaging the inner surface of said body whereby said top is secured upon said body, an external lid rotatable upon said body, a cutter carried by said external lid, 80 and arranged to cut through said annulus and means for moving said cutter into cutting engagement with said annulus when said external lid is rotated, said cutter having a hard cutting point and a relatively 85 softer portion remote from said point whereby the latter is bent by engagement with the cut annulus as the external lid is removed from the body.

2. An air-tight canister having a thin 90 metal top sealed thereto, an external lid rotatable upon the canister, a cutter carried by said external lid and extending in the plane of rotation thereof, means for moving said cutter into operative position when said external lid is rotated, a hard point on said cutter, a portion of said cutter remote from said point being softer than said point, a peripheral flange on said thin metal top, a portion of reduced diameter at the upper 95 end of said canister of substantially the same depth in the direction of the axis of the canister, as said peripheral flange, the reduction in diameter being substantially equal to twice the thickness of said thin metal top. 100

3. An air-tight canister having a thin metal top sealed thereto, an external lid rotatable upon the canister, a peripheral flange on said external lid furnished externally 105

with a series of protuberances, a cutter carried by said external lid and extending in the plane of rotation thereof, means for moving said cutter into operative position when said external lid is rotated, a hard point on said cutter, a portion of said cutter remote from said point being softer than said point, a peripheral flange on said thin metal top, a portion of reduced diameter at the upper end of said canister of substantially the same depth, in the direction of the axis of the canister, as the peripheral flange on said thin metal top, the reduction in diameter being substantially equal to twice the thickness of said thin metal top. 115

WALTER JOHN FRYER.
